(57) **CLAIM**

The ornamental design for a light incorporating a clip and bottle opener, as shown and described.

DESCRIPTION

FIG. 1 is a top perspective view of a light incorporating a clip and bottle opener;

FIG. 2 is a top plan view thereof;

FIG. 3 is a front elevation view thereof;

FIG. 4 is a right elevation view thereof;

FIG. 5 is a left elevation view thereof; and,

FIG. 6 is an environmental drawing showing the light opening a bottle.

The broken lines showing a bottle and bottle cap depict environmental subject matter only and form no part of the claimed design.
